UNITED STATES PATENT OFFICE.

LEWIS D. TUCKER, OF GLOUCESTER, MASSACHUSETTS.

TOILET BOWL.

Application filed July 26, 1920. Serial No. 398,868.

To all whom it may concern:

Be it known that I, LEWIS D. TUCKER, a citizen of the United States, residing at Gloucester, in the county of Essex and State 5 of Massachusetts, have invented certain new and useful Improvements in Toilet Bowls; and I do declare the following to be a full, clear, and exact description of the invention, such as will enable others skilled in the art 10 to which it appertains to make and use the same.

This invention relates to an improved toilet bowl and one object of the invention is to provide a bowl having an improved 15 construction whereby the bowl is provided with an overflow passage communicating with the outlet so that in case the outlet should become choked and the bowl filled, surplus water may pass into the overflow 20 outlet and down into the main outlet.

Another object of the invention is to so construct the overflow outlet that a water seal may be formed therein similar to the water seal usually provided in the lower portion 25 of a bowl.

Another object of the invention is to so construct this bowl that water may be fed into the overflow outlet from the main supply conduit and thus the water seal of the 30 overflow outlet kept filled.

Another object of the invention is to so construct this overflow outlet that a drain may be provided for draining the water seal thereof when necessary.

Another object of the invention is to so construct this bowl that the auxiliary or overflow outlet may be provided with a removable cap for cleaning purposes.

This invention is illustrated in the accompanying drawings, wherein:—

Figure 1 is a view showing the improved bowl partially in front elevation and partially in vertical section,

Figure 2 is a view showing the improved bowl partially in side elevation and partially in vertical section,

Figure 3 is a top plan view of the improved bowl,

Figure 4 is a view showing the bowl in rear elevation, the overflow outlet being shown in section along the line 4—4 of Fig. 3, and

Figure 5 is a fragmentary sectional view taken along the line 5—5 of Fig. 3.

This improved bowl 1 in general appearance resembles an ordinary bowl and is

provided with an outlet 2 and baffle plates or partitions 3 and 4 so that the usual sink 5 is provided for forming a water seal when this sink is filled with water as shown 60 in Fig. 2. The usual water inlet passage 6 is provided and also the usual annular water passage 7 and a baffle plate 8 extends downwardly in front of the main water inlet passage 6 so that water entering the bowl 65 through this passage will be directed downwardly into the sink and out through the outlet 2. It will thus be seen that when the device is in operation, water from the reservoir tank 9 will pass through the pipe 10 70 and through the inlet 6 into the bowl where it will strike the plate 8 and be directed downwardly.

It sometimes happens that the outlet passage 2 will become choked above or below 75 the partition or baffle 4 and the bowl will then fill since water cannot pass freely through the outlet passage 2 which causes the bowl to overflow and it is to overcome this objection that the improved construction 80 has been provided. In order to prevent the bowl from overflowing, there has been provided an overflow passage 11 which communicates with the outlet beneath the sink as shown in Fig. 2 and extends upwardly through the rear wall of the bowl.

The overflow passage 11 is provided with an enlarged upper end portion which extends beneath and upon opposite sides of the conduit 6 through which water passes 90 into the bowl and the baffle plate 12 is provided in the upper portion of this overflow passage as shown in Fig. 4 thus providing a sink which will fill with water and thus form a water seal. It should be noted that 95 the water passage or conduit 6 is provided with an opening 14 through which water may pass to fill this sink 13 and thus insure the provision of a water seal at the upper end of this overflow passage 11 and further 100 that the rear wall of the sink is provided with a drain opening normally closed by a threaded plug 15 which may be removed when it is desired to drain the sink 13 for any reason.

The entrance side of this overflow sink 13 is provided with a main inlet opening 16 communicating with the bowl and with smaller auxiliary inlet openings 17 and in order to permit ready access to the sink 13 for cleaning or repairing purposes, there has been provided a removable cover plate 18 which closes the upper end 105 110

as shown in Figs. 4 and 5 and is releasably held in place by bolts or other removable fasteners 19. From an inspection of Fig. 5 it will be further noted that this sink is 5 provided with a branch arm 20 which extends through the rear wall and will be normally closed by a suitable plug or cap 21 as shown in Fig. 3.

When this bowl is in use, water from the 10 reservoir passes through the pipe 10 into the conduit 6 and through this conduit into the bowl, a certain portion of the water passing through the opening 14 into the sink 13. The opening 14 is, however, a comparatively small opening and therefore the major portion of the water will pass directly through the conduit and only a small portion pass through the opening 14, this amount, however, being sufficient to keep the 15 sink 13 filled. It is further noted that since the sink is filled to the point shown in Fig. 4, a certain amount of the water in this sink will be drawn out as the water passes through the conduit 6 and this will be replaced by fresh water thus keeping the water in the sink from becoming stagnant. If the outlet passage 21 should become choked in anyway, the bowl will fill and the 20 surplus water which ordinarily would overflow, 25 will pass through the overflow openings 16 and 17 into the overflow passage and will pass down through this passage 11 and out through the main outlet beneath the parti-

tion or baffle 4. It will thus be seen that danger of the bowl overflowing will be 35 avoided and flooring and woodwork will be saved from damage.

What is claimed is:

A bowl having an outlet and having a conductor pipe extending transversely 40 through the wall of the bowl adjacent the upper end thereof for supplying water to the bowl, the bowl having in its walls a vertically disposed overflow passage having its lower end communicating with the outlet 45 of the bowl and having its upper end portion provided with arms extending upon opposite sides of the conductor pipe, one arm having a side opening forming an inlet communicating with the interior of the bowl, 50 and a baffle plate positioned in the upper portion of the overflow passage at the lower end of the arm thereof and extending beneath and partially about the water supply pipe of the bowl to provide a water seal 55 sink, the water supply pipe of the bowl having an opening for feeding water to the water seal sink.

In testimony whereof I have hereunto set my hand in the presence of two subscribing 60 witnesses.

LEWIS D. TUCKER.
